ARCHIBALD BLACK, OF GARDEN CITY, NEW YORK.

FLOTATION DEVICE.

Application filed December 3, 1926. Serial No. 152,423.

- My invention relates to flotation devices designed to support a weight upon the surface of a body of water. While capable of quite general application it is of particular value when applied to an emergency flotation gear of the type used on land types of aircraft to permit their being safely landed upon water. In aircraft emergency flotation gears, the flotation is provided by the 5 use of fabric bags which are normally folded up but which can be unrolled and inflated when it is intended to land upon water. The customary practice in constructing such devices is to provide a container of compressed 10 air under the control of a member of the crew of the aircraft. When it becomes necessary to inflate the flotation bags, this compressed air is fed from the high pressure container into the fabric bags and is held 15 therein by a check valve to prevent the bags from becoming deflated after the operation of inflation is completed. In some such installations, and for the purpose of decreasing the size of the compressed air tank necessary, 20 25 30 35 40 45 50 55 60 65 70 75 80 85 90 95 100 105
- The use of tanks of compressed air in this way is usually undesirable as they are subject to leakage and may therefore be found incapable of fully inflating the flotation gear at a critical time. Furthermore, it is not practicable to carry an air tank having sufficient capacity to allow more than one inflation as such a tank would be excessively heavy. Thus, if the air bags should happen to develop a slow leak, they could not be re-inflated and the aircraft might sink before aid could be secured.
- In my invention I substitute for the customary compressed air tank a means whereby 45 50 55 60 65 70 75 80 85 90 95 100 105
- by gaseous products of combustion may be conveyed into the flotation bags, or such, for the purpose of their inflation. Inasmuch as these gaseous products of combustion have an initial high temperature upon generation 50 which is too great to permit injecting them directly into the flotation means, I interpose a cooling chamber or chambers for the gases between the combustion chamber and the flotation bag or such. I may also combine this
- cooling chamber or chambers with an injection device for drawing external air into the flotation system. In the application of my system I may use various well known methods of producing gases by combustion. I prefer, however, to utilize such a material as that commonly known as "smokeless powder" as this material is conveniently available in commerce, is safe to handle and does not deteriorate appreciably if stored without being used for an extended period. Consequently, the inflation device might remain in the aircraft for a period of a few years without being recharged and yet be capable of rapid and efficient operation in an emergency. To further improve the safe and convenient operation of my device, I provide a multiplicity of inflation charges, means for preventing accidental operation of the device, means for automatically igniting a charge upon operation of the device and means for limiting the internal pressure in each combustion chamber to prevent explosion thereof.
- In the accompanying drawings Fig. 1, is a side view of an airplane equipped with a flotation gear constructed according to my invention, while Fig. 2, is an enlarged view of a portion of the same illustrating the arrangement of the installation. Fig. 3, is a vertical section through the gas generating device which is shown installed in Fig. 2, and Fig. 4, shows a section through the upper portion of the gas generator control and operating mechanism drawn on a considerably enlarged scale. Fig. 5, is a cross section through the generator control mechanism on the line A—A, in Fig. 4, looking in the direction of the arrows, while Fig. 6, is a similar cross section on the line B—B, and Fig. 7, is a cross section on the line C—C. Fig. 8, is a plan view of the device used to ignite the charges, a portion being shown cut away to expose the percussion cap. Fig. 9, is a side view of the ignition device shown in Fig. 8. Fig. 10, is a vertical section through the center of the injector shown in Fig. 2, illustrating its interior arrangement and showing the self-closing flap valve used to prevent escape of air and gases from the flotation bag. Fig. 11, is a section through the air intake on the line D—D, in Fig. 2, looking in the direction indicated by the arrows and with the door in the closed position. Fig. 12, is a sec-

tion similar to that shown in Fig. 11, but with the door in the open position.

In Figs. 1, and 2, the airplane is provided with a flotation bag 1, on each side and in such position that the bags will sustain the machine upon the surface of the water when they are inflated. The gases for inflation of bags 1, are supplied by a gas generator 2, or by two such, installed within control of the pilot or some other member of the crew of the airplane. Generator 2, is shown in Fig. 3, to contain charges 3, each containing a quantity of smokeless powder 4, a firing material 5, and an ignition device 6. Chambers 7, and 8, are provided to permit some expansion of the gases released by combustion of powder 4, and slots 9, 10, and 11, are provided in a control valve stem 12 to permit passage of the gases from chamber 7, to chamber 8. I may also provide chamber 8, with a pressure gauge 13, to indicate the pressure therein. Valve stem 12, is rotated by a handle 14, and, as will be shown hereinafter, is provided with means for preventing its unintentional operation as well as with means for operating the ignition devices 6. To eliminate danger of explosion in event of excessive pressure being generated within the apparatus during the combustion, I provide each chamber 7, with a safety valve 15, shown in Fig. 2, and arranged to discharge the gases outside of the body of the airplane when a predetermined maximum safe internal pressure is attained.

In Figs. 4, 5, 6, and 7, the means for preventing unintentional operation of valve stem 12 are shown. Handle 14, is mounted to move freely endwise in stem 12, and is provided with pins 16, which engage the sides of a slot 17, in stem 12, so that rotary movement of handle 14, is transmitted to stem 12. To prevent unintentional operation of the device, handle 14, is provided with a pin 18, adapted to move only within slots 19, in block 20, and slots 21, in block 22, while blocks 20, and 22, are held against rotation by pins 23. Slots 19, and 21, are staggered with respect to each other but sufficient overlapping is provided to permit pin 18, to pass from one of the slots 19, to the adjacent slot 21, when handle 14, is moved endwise. With this arrangement handle 14, can be turned through a small angle at each rotary movement and the device is so proportioned that this angle is just sufficient to operate one igniter 6, only. To operate the second igniter 6, it becomes necessary to first move handle 14, endwise and then to rotate it a further portion of a turn. To operate the third igniter 6, it becomes necessary to again move handle 14, endwise, this time in the opposite direction. Each successive movement brings one of the slots 9, 10, or 11, into alignment with its respective chamber 7, thus permitting escape of

the gases from chamber 7, to chamber 8, but preventing backward flow of hot gases from chamber 8, into the other chambers 7, which flow would ignite an unburned charge of powder 4.

In Figs. 8, and 9, ignition device 6, is shown to consist of a percussion cap 24, adapted to be ignited by a striking point 25, actuated by a spring 26, when the device is operated. Normally, spring 26, is held against operation by a toggle 27, mounted on a sliding rod 28, and engaging frame 29, of igniter 6, in such manner as to hold spring 26, in compression. When the device is operated, the rotation of valve stem 12, causes a notch 30, thereon to engage a trigger 31, formed on the toggle 27, and causes toggle 27, to rotate to the position indicated by dotted lines 32, and thus releasing the restraining effort from spring 26, and permitting it to drive point 25, against percussion cap 24. The impact ignites cap 24, which ignites firing material 5, shown in Fig. 3, and which in turn ignites powder 4, causing the device to produce gases of combustion which flow from chamber 7, through the corresponding slot 9, 10, or 11, as the case may be, into chamber 8. From chamber 8, the gases flow into an injector 33, as shown in Figs. 2, and 10, through a nozzle 34. Injector 33, is formed on the Venturi principle and is arranged so that the suction set up by the flow of gases from nozzle 34, draws air from the atmosphere through a door 35, the operation of which will be described hereinafter. This external air drawn into injector 33, becomes mixed with the gases flowing from nozzle 34, and serves to reduce the temperature of these as well as to increase their volume. To further reduce the temperature of the gases, I provide radiating fins 36, on the outside of injector 33, for the purpose of radiating heat to the external atmosphere. The mixture of gases and air flowing through injector 33, passes through an opening 37, in flotation bag 1, and causes the said bag to become inflated.

As the powder 4, becomes consumed, the flow of gases and air through injector 33, gradually drops until they can no longer be forced into bag 1, against the internal pressure which has been created therein. When this condition is reached the gases and air tend to flow in a reverse direction from bag 1, through opening 37, to the external atmosphere, whereupon a flap valve 38, is drawn against opening 37, by the initial reverse flow of gases therethrough and thus the opening 37, is closed to prevent further outflow of gases.

To prevent partial inflation of bag 1, by the inflow of external air when such is not desired, I arrange door 35, so that it may be operated by a member of the crew of the aircraft as shown in Figs. 11, and 12. Nor-

mally, door 35, remains in the closed position as shown in Fig. 11. When the inflation is desired, and just previous to operation of the gas generating mechanism al-
5 ready described, door 35, is opened by means of a handle 39, to the position shown in Fig. 12, whereupon air may flow through it into injector 33.

In operation of my device, door 35, is 10 first opened by a member of the crew and handle 14, is then rotated to cause operation of the ignition device in the manner already described. The combustion of powder 4, in one of the charges 3, then produces gases 15 which flow through the generating and injecting mechanisms and are cooled and mixed with air drawn into the system from the atmosphere and then injected into the flotation bags in the manner described. If it should 20 become desirable to reinflate the bags for any reason whatsoever, handle 14, may be moved endwise and again rotated to bring a second charge 3, into use as described.

Although I have shown and described my 25 invention as applied to an aircraft flotation gear, it will be obvious that it might be applied to equal advantage in other cases where it is desired to provide means for quickly expanding a container to float a boat, raft, 30 life-belt, or other life-saving or other buoyant appliance.

Having thus described my invention, I claim:

1. A flotation device comprising, combustion apparatus, a duct for conveying the gases produced by the combustion, and a container for receiving the said gases and adapted to provide flotation upon water.

2. A flotation device comprising, combustion apparatus, a duct for conveying the gases produced by the combustion, a container for receiving the said gases and adapted to provide flotation upon water, and a safety valve to permit the escape of excess 45 pressure from within the system.

3. A flotation device comprising, combustion apparatus, a duct for conveying the gases produced by the combustion, a container for receiving the said gases and adapted to provide flotation upon water, and a safety valve communicating to the exterior of the device to permit the escape of excess pressure from within the system.

4. A flotation device comprising, combustion apparatus, a duct for conveying the gases produced by the combustion, a con-

tainer for receiving the said gases and adapted to provide flotation upon water, and a heat radiating chamber for the radiation of the heat of the gases.

5. A flotation device comprising, combustion apparatus, a duct for conveying the gases produced by the combustion, a container for receiving the said gases and adapted to provide flotation upon water, and means for preventing unintentional operation of the device.

6. A flotation device comprising, combustion apparatus, a duct for conveying the gases produced by the combustion, a container for receiving the said gases and adapted to provide flotation upon water, and an injector for injecting atmospheric air with the gases of combustion into the container.

7. A combustion device for the generation 75 of gas pressure for expanding a flotation appliance, comprising a chamber for the generation of gases of combustion, a duct for conveying the gases from the said chamber to the appliance, and a release valve to permit escape of the gases from the chamber when a predetermined internal pressure is exceeded.

8. A combustion device for the generation 85 of gas pressure for expanding a flotation appliance, comprising a chamber for the generation of gases of combustion, a duct for conveying the gases from the said chamber to the appliance, and a heat radiating chamber wherein the excess heat of combustion is 90 radiated to the external atmosphere.

9. A combustion device for the generation 95 of gas pressure for expanding a flotation appliance, comprising a chamber for the generation of gases of combustion, a duct for conveying the gases from the said chamber to the appliance, and means for preventing unintentional operation of the device.

10. A combustion device for the generation 100 of gas pressure, comprising a plurality of chambers containing pressure producing charges, a common compartment capable of communication with said chambers, and means for igniting the charges in individual chambers and for selectively establishing 105 communication between the common compartment and the chamber containing the ignited charge.

In testimony whereof, I have signed my name to this specification, this 29th day of November 1926.

ARCHIBALD BLACK.
